UNITED STATES PATENT OFFICE.

HERBERT M. STURGIS, OF KANSAS CITY, MISSOURI.

MOP AND BRUSH HANDLE CONNECTION.

Application filed April 20, 1925. Serial No. 24,465.

This invention relates to mop and brush handle connections, but it is particularly designed for use in connection with a mop head such as is usually employed with floor 5 mops, and the invention particularly resides in the frame for holding the mop fabric which is usually in the form of a bag.

The invention consists in certain parts and combinations of parts, all of which will 10 be specifically described hereinafter, reference being had to the accompanying drawings, in which—

Fig. 1 is a perspective view of the mop head frame showing the handle attached, 15 and

Fig. 2 is a perspective view of the mop head frame with the handle-attaching clips removed.

The frame is shown as constructed of a 20 piece of stout wire bent intermediate its ends to provide a toe portion 1 with diverging side members or bars 2 and 3 terminating at their rear ends in inwardly disposed heel forming portions 4 and 5, the 25 heel forming portions being spaced apart longitudinally of the frame. The wire extends forwardly toward the toe 1 and about midway of the frame it is curved outwardly as at 6 and 7 so that the two heel brace bars 30 8 and 9 may be secured to the side bars 2 and 3 by spot welding indicated at 10 and 11. The ends of the wires are directed transversely across the frame in overlapping relation in opposite directions, each end 35 having a right-angularly projecting terminal abutting against the other end portion. The two end portions are indicated at 12 and 13. The end portion 12 is provided with an off-set or shoulder 14 against which 40 the right-angularly projecting terminal 15 of the end member 13 abuts. The right-angularly projecting portion 16 of the end portion 12 abuts against the edge of the portion 13. The sides of the portions 12 45 and 13 are flat as indicated at 17 and 18 to receive a sheet metal clip 19 which is folded around the transversely disposed end portions 12 and 13 to securely fasten them together to form a transverse intermediate 50 brace. The clip 19 is provided with an edge cut-out portion 20 on either side of which is a pivot-receiving tubular portion. These 55 are indicated at 21 and 22 to receive the oppositely disposed pivot members 23 and 24 of a looped member 25 which is carried by

the ferrule 26 which receives the end of the handle 27.

The handle will be so fastened to the clip that it will pass through the space between the heel portions of the frame when the 60 frame is tilted on the members 23 and 24. The frame may be caused to lie flat upon the floor and the toe portion will enable the operator to move the mop into angular places such as corners and the like, and the 65 flat construction of the frame will permit mopping or polishing under furniture, radiators and the like.

The frame may be inexpensively constructed from wire as will be apparent by 70 reference to the foregoing description in connection with the drawings. The wire may be of appropriate gauge and when it is formed as shown in the illustrated embodiment of the invention, it will possess 75 considerable rigidity and yet require but little weight.

What I claim and desire to secure by Letters-Patent is:

1. A mop head, comprising a frame consisting of wire bent intermediate its ends to provide a toe with two diverging side portions, two inwardly extending heel portions in spaced relation, brace bars integral with the heel portions and connected to the side 80 portions intermediate their ends, the ends of the wire extending across the middle of the frame in overlapping relation, and having right angular terminals, the terminal at one end portion abutting against the other 85 end portion, a clip fastening the two end portions together, and a handle fastening pivotally fastened to the clip.

2. A mop head, comprising a frame consisting of a single strand of stout wire, bent at its middle to provide a toe portion and two diverging side bar portions, the side bar portions having inbent heel portions at their ends opposite the toe, the heel portions being backturned and having outwardly curved portions secured to the intermediate portions of the side bar portions, the ends of the wire strand being inturned and overlapping at the middle of the frame, a clip connecting the overlapped 100 ends of the wire strand, and a handle fastening pivoted to the clip.

3. A mop head, comprising a frame consisting of a single strand of stout wire formed into a frame, having a wedge- 110

- shaped toe and two spaced, inwardly extending heel portions, the heels having forwardly extended portions connected to intermediate side portions of the frame, the 5 free ends of the strand extending inwardly across the middle of the frame in overlapping relation, a clip connecting the overlapping ends of the strand, and a handle fastening pivotally secured to the clip.
- 10 4. A mop head, comprising a frame consisting of a single strand of stout wire formed into a frame, having a wedge-shaped toe portion and two spaced, inwardly extending heel portions, the innermost por-

tions of the heels having laterally bent portions connected to intermediate side portions of the frame, the free ends of the strand extending inwardly across the middle of the frame, in overlapping relation, the overlapping ends of the wire having flat sides, a clip connecting the overlapped ends of the strand and having side walls lying flush against the flat sides thereon, and a handle fastening pivotally secured to the clip. 15

20 In testimony whereof I affix my signature.

25 HERBERT M. STURGIS.
